CLAIM

The ornamental design for a combined paper stacker and baler, as shown and described.

DESCRIPTION

FIG. 1 is a side elevational view of a combined paper stacker and baler showing my new design, the broken line disclosure of a rope being shown for illustrative purposes only;

FIG. 2 is a side elevational view opposite that shown in FIG. 1;

FIG. 3 is a front elevational view thereof;

FIG. 4 is a rear elevational view thereof;

FIG. 5 is a top plan view thereof;

FIG. 6 is a bottom plan view thereof.
